CLAIM

The ornamental design for cable drum, as shown and described.

DESCRIPTION

FIG. 1 is a front, right hand side perspective view of a cable drum embodying my new design;

FIG. 2 is a front view thereof;

FIG. 3 is a rear view thereof;

FIG. 4 is a side view thereof as seen from the right hand side of FIG. 2;

FIG. 5 is a side view thereof as seen from the left hand side of FIG. 2;

FIG. 6 is a top view thereof;

FIG. 7 is a bottom view thereof;

FIG. 8 is a rear, left hand side perspective view thereof; and, FIG. 9 is a front, top, right hand side perspective view thereof.

The broken lines in the drawing depict environmental subject matter only and form no part of the claimed design.
